(**) Term: **15 Years**

* cited by examiner

(21) Appl. No.: **29/581,640**

Primary Examiner — Robert A Delehanty

(22) Filed: **Oct. 20, 2016**

(74) *Attorney, Agent, or Firm* — Edell, Shapiro & Finn, LLC

(51) LOC (11) Cl. **29-02**

CLAIM

(52) U.S. Cl.

The ornamental design for a welding helmet, as shown and described.

USPC **D29/110**

DESCRIPTION

(58) **Field of Classification Search**

USPC D29/110, 102, 106–107, 122; D24/110.1,

D24/110.2, 110.3
FIG. 1 is a front isometric view of my new design;

D24/110.3

CPC .. A61F 9/06; A61F 9/061; A61F 9/064; A61F

FIG. 2 is a rear isometric view of the design of FIG. 1;

9/065; A61F 9/067; A61F 9/068

FIG. 3 is a front isometric view of the design of FIG. 1 with the neck guard in a detached configuration;

See application file for complete search history.

FIG. 4 is a rear isometric view of the design of FIG. 1 with the neck guard in a detached configuration;
